UNITED STATES PATENT OFFICE.

JOHN P. IRWIN, OF ROCKY RIVER, OHIO, ASSIGNOR TO ARTHUR G. MCKEE & COMPANY, OF CLEVELAND, OHIO, A CORPORATION OF DELAWARE.

SELF-PROPELLED RAIL CAR.

Application filed October 13, 1924. Serial No. 743,242.

The present improvements, relating, as indicated, to self propelled rail cars, have more particular regard to cars designed for industrial use as for the haulage of materials about plants, mines and the like. It will be understood, however, that the novel features of construction presented may be employed in rail cars of other types and designed for widely different uses.

One principal object of the invention is to provide a self propelled rail car in which the motive power is derived from an internal combustion (gas or oil) engine. Another object is to support such engine with accessory operating elements, as well as necessary control and operating elements for the car proper, on a truck frame that is capable of swiveling independently of the main frame of the car proper. To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a side elevation of a self propelled rail car embodying my present improvements; Fig. 2 is a broken plan view of the same; Fig. 3 is a rear elevation thereof, the car being viewed from the left as shown in Fig. 1; and Fig. 4 is a broken transverse section taken on the plane indicated by the lines 4—4, Figs. 1 and 2.

The particular type of car illustrated in the drawings is an ore transfer car such as used about blast furnaces for hauling ore or other materials from one point to another. The car is accordingly provided with a hopper body 1, the lower portions of the sides whereof slope inwardly so that the material may be discharged on either side of the oppositely sloping bottom 2 by opening one or the other of the hinged gates 3. Two sets of toggles 4, each operated by means of a pressure fluid cylinder 5 with piston (not shown), are provided for opening the gates 3 or retaining them closed as desired. Such operating cylinders and pistons, as shown in Fig. 1, are preferably located at one end of the car body 1 and adjacent thereto air

tanks 6 are carried in the framework 7 that supports the corresponding end of the body.

Such body and framework 7 are built upon a main frame 8 of more or less standard construction, the principal members composing such frame being two longitudinal beams or sills 9, one on each side, which extend to the right far enough to have swiveled support upon a standard car truck 10. At the opposite end the beams 9 project similarly beyond the corresponding end of the body 1 and are united at their ends by a cross-beam or bolster 12. The latter is centrally supported by a swiveled mounting 13, preferably provided with anti-friction rollers on a truck 14 of special design. This truck is in effect an independent tractor unit, being provided with a platform 15 that lies above and clear of the cross-beam or bolster 12 and serves as a support for the engine by which the truck and thus the car are propelled. Such engine is housed within a hood 16, similar to that regularly employed in motor trucks, and to the rear of such hood is located a cab 17 for the operator.

As best shown in Fig. 1, the portions 14^a of the side-frame members composing truck 14, that lie intermediate of the axles 18 are dropped below the ends of said members and so provide ample space for any oscillation of the bolster 12 relatively to the truck. The truck springs 19, it will be noted, are interposed between the journals of the axles and the portions of such side-frame members in which such axles are held. The latter are thus permitted necessary independent vertical movement in passing over an uneven track.

The one side of cab 17, as best shown in Fig. 2, is offset with respect to the center line so as to provide clear vision forward and back for the operator, the seat 20 which is located adjacent this side being reversible in position, as indicated in dotted outline, and the cab where thus extending beyond the platform and over the beam or sill 9, sets sufficiently above to afford clearance. The fuel tank 21 is preferably located between the hood 16 and cab 17, as is also an air compressor 22, while all the elements for controlling the operation of the engine are located in the cab 17 conveniently within the reach of the operator when occupying seat 20. As shown, such elements include a

clutch pedal 23, gas throttle 24, brake valve 25 and spark lever 26, together with a gear shift lever 27. In addition to the control devices for the engine and motor truck 14, 5 there are also located in the cab, adjacent to the operator's seat, valves 29 for controlling the operation of the gates 3 where a hopper body of the type described is employed, and valves 30 for operating the usual 10 sanding devices to prevent slipping of the wheels on the rails.

The driving connections between the engine and the wheels 31 are preferably of the sprocket chain type, one such chain 32 15 connecting a transverse shaft 33 on platform 15 with the rear wheels 31 of said truck and another chain 34 connecting such rear wheels with the forward wheels. It will be understood that said transverse shaft 20 33 is driven from the engine through a transmission gear of standard construction, such gear being shifted to change the speed by means of the lever 27 heretofore referred to.

25 As a result of the foregoing construction, it will be seen that the tractor unit comprising truck 14 with engine and operator's cab mounted thereon is in effect independent of the car body 2 or rear of the main frame 8, on which such body is supported, except as the one end of the latter has a swivel connection with said truck. All the elements for controlling the operation of the engine, as well as the braking and sanding 30 35 devices of the car and the gate operating devices, where the car body is of a type including these, are located conveniently within reach of the operator in the cab 17. A single operator is thus enabled to run the car without assistance and yet with entire safety.

Other modes of applying the principle of my invention may be employed instead of the one explained, change being made as 45 regards the mechanism herein disclosed, provided the means stated by any of the following claims or the equivalent of such stated means be employed.

I therefore particularly point out and 50 distinctly claim as my invention:

1. In a self-propelled rail car, the combination of a supporting truck; a drive truck; and a car having walls and main frame sills, said drive truck having an operating platform spaced endwise from said car walls and disposed for clearance within the sills on swiveling movement of said truck, an engine for driving said truck mounted on said platform, and control elements both 55 for said engine and for the car proper likewise mounted on said platform.

2. In a self-propelled rail car, the combination of a supporting truck; a drive truck; and a main car frame swiveled at its ends 60 on said trucks respectively, said drive truck

including side frame members with depressed portions intermediate of their ends and a transverse member connecting such depressed portions whereon said main car frame is thus swiveled, the axles of the truck 70 being mounted in corresponding ends of said side frame members, compression springs interposed between said axles and members, and a platform supported on the ends of said side frame members so as to clear said main 75 car frame.

3. In a self-propelled car, the combination of a standard truck; a tractor truck; a transverse bolster swiveled on said tractor truck; a main frame swiveled at one end on said standard truck and including longitudinal beams supported at the other end of said frame on said bolster; a car body on said frame; hinged gates in said body; an engine platform supported on said tractor truck independently of said main frame, said platform lying above the bolster and between the beams of said main frame; and control elements carried on the platform for 80 85 said engine and for said gates. 90

4. In a self-propelled car, the combination of a supporting truck; a drive truck, a transverse bolster swiveled on said drive truck at a point intermediate of the front and rear wheels thereof; a main frame swiveled at 95 one end on said supporting truck and including longitudinal beams terminating at the other end of said frame on said bolster; a platform supported on said drive truck independently of said main frame, said platform lying above the bolster and between the beams of the main frame; and an engine mounted on said platform and having driving 100 connections with the truck wheels. 100

5. In a self-propelled car, the combination of a standard truck; a tractor truck; a transverse bolster swiveled on said tractor truck at a point intermediate of the front and rear wheels thereof; a main frame swiveled at 105 one end on said standard truck and including longitudinal beams supported at the other end of said frame on said bolster; a platform supported on said tractor truck independently of said main frame, said platform lying above said bolster and between 110 the beams of said main frame; an engine mounted on the forward portion of said platform and having driving connections with the rear wheels thereof; and an operator's cab mounted on the rear portion of said 115 platform and extending laterally above said beams. 120

6. In a self-propelled car, the combination of a standard truck; a tractor truck, said tractor truck including side frame members 125 with depressed portions intermediate of their ends and a transverse member connecting such depressed portions; a transverse bolster swiveled on said transverse member; a main frame swiveled at one end on said 130

standard truck and including longitudinal beams supported at the other end of said frame on said bolster; a platform supported on said tractor truck independently of said main frame, said platform lying above said bolster and between the beams of said main frame; an engine mounted on the forward end of said platform and having driving

connections with the rear wheels thereof; and an operator's cab mounted on the rear portion of said platform and extending laterally above said beams. 10

Signed by me, this 10th day of October, 1924.

JOHN P. IRWIN.
